[57] CLAIM

The ornamental design for a merchandising display frame, as shown and described.

DESCRIPTION

FIG. 1 is a top perspective view of a merchandising display frame showing our new design;

FIG. 2 is a front elevational view thereof;

FIG. 3 is a left side elevational view, the right side view being a mirror image thereof;

FIG. 4 is a rear elevational view thereof;

FIG. 5 is a top plan view thereof;

FIG. 6 is a bottom plan view thereof;

FIG. 7 is a perspective view of another embodiment of the merchandising display frame shown in FIG. 1, the opposite side being a mirror image thereof;

FIG. 8 is a front elevational view thereof; and

FIG. 9 is a left side elevational view, the right side view being a mirror image thereof.

FIG. 1
